UNITED STATES PATENT OFFICE.

WILLIAM J. BRADSHAW AND WILLIAM W. COWLEY, OF CLEVELAND, OHIO.

DEVICE FOR FEEDING AIR TO FURNACES.

SPECIFICATION forming part of Letters Patent No. 275,574, dated April 10, 1883.

Application filed April 6, 1882. (No model.)

To all whom it may concern:

Be it known that we, WILLIAM J. BRADSHAW and WILLIAM W. COWLEY, citizens of the United States of America, residing at 5 Cleveland, in the county of Cuyahoga and State of Ohio, have invented certain new and useful Improvements in Devices for Feeding Air to Furnaces; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in devices for feeding air to furnaces; and it consists in the arrangement of a series of air and steam injector-pipes having within a conical section of the pipes spirally-arranged webs, whereby the combined steam and air, as they are injected over the fire-surface, will have a whirling motion, and more thoroughly agitate the smoke and gases as they rise over the fuel, and produce a better combustion and large saving of fuel, and leave but little smoke, all of which will be hereinafter more fully described.

Figure 1 is an elevation of the front end of 30 a boiler and furnace, showing the arrangement of the steam-pipe. Fig. 2 is a side elevation of the boiler and furnace, partly in section, showing the fire-box and the injection-pipe. Figs. 3 and 4 are sections of an injector-tube, showing the spiral webs. Fig. 35 5 is an end view of the conical section of the injection-pipe. Fig. 6 is a view of the collar to support the steam-jet pipe. Fig. 7 is a section of the steam-jet pipe. Fig. 8 is an enlarged section of the fire-box. Fig. 9 is a sectional view of the device enlarged and a part 40 of a furnace, showing the smoke-box and end of the boiler. Fig. 10 is a front view of the head F' in Fig. 9.

45 A represents the boiler, which is stationary and set, in the usual manner, in brick masonry, and to which this improvement is applied by having suitable holes made in the masonry immediately over each fire-door and

between these or wherever it may be required 50 site for an injector-pipe to be placed.

B is the fire-box.

C is a steam-pipe, which is connected with the steam-dome on top of the boiler, and is carried along the top of the boiler and down 55 in front, and thence across the front, as seen in Fig. 1, where it is properly supported at a a. At c c' c² there are branch jet-pipes C', of the construction shown in Fig. 7, which are within the entrance of the short pipe D, which is cylindrical, and has connected with it inwardly 60 a conical section, E, widening toward the fire-box. To the outer end of the tube D there is attached the collar F, which has a central bearing, f, for the support of the end c³ of 65 the steam-jet C', as shown in Fig. 6. In the construction of this pipe the short tube D may be threaded at each end, and the conical section E and the collar F can be screwed on; or the whole pipe may be made in one piece. 70 In the conical section E there are arranged several spiral webs, e e e e, as represented in Figs. 3, 4, and 5, similar to the webs of a ship's propeller, the purpose of which is to give the steam and air a rotary and spiral 75 movement inwardly as they pass into the fire-box and over the burning fuel. The collar F being much larger than the steam-jet pipe C', and also being open to the outer air, as shown in Fig. 2 by the arrows at b b, the air 80 is freely admitted within the pipe D, and, with the steam from the jet-pipe c³, passes into the fire-box in such proportion and quantity as properly to aid in the combustion of the ascending gases over the fuel and greatly to 85 economize the fuel. The steam and air combined, passing through the spirally-arranged webs within the conical section, obtain a spiral movement which will continue to a considerable distance within the fire-box, and by 90 this action keep the products of the combustion of the fuel longer over the fire, and consequently burn them more thoroughly before they pass beyond the bridge-wall and into the upward draft.

95 We claim—

In steam and air injectors for aiding combustion, a stationary injector-pipe consisting of

the straight pipe D and conical section E, said conical section opening into the furnace, and having four spirally-arranged webs or projections running the entire length and extending nearly half-way across said conical section, leaving the center of the pipe entirely open, in combination with a stationary steam-jet pipe projecting into the tube D, substantially as and for the purpose shown and described.

In testimony whereof we affix our signatures in presence of two witnesses.

WILLIAM J. BRADSHAW.
WILLIAM W. COWLEY.
